(57) **CLAIM**

The ornamental design for a part of a metering pump, as
shown and described.

DESCRIPTION

The file of this patent contains at least one drawing/photograph
executed in color. Copies of this patent with color
drawing(s)/photograph(s) will be provided by the Office upon
request and payment of the necessary fee.

FIG. 1 is a side view of the invention;

FIG. 2 is a top view of the invention in an "OFF" position;

FIG. 3 is a top view of the invention in an "ON" position; and,

FIG. 4 is a front view of the invention.
